UNITED STATES PATENT OFFICE

BENJAMIN S. NASH, OF SHORT HILLS, NEW JERSEY, ASSIGNOR TO THE STEARNS & FOSTER COMPANY, OF LOCKLAND, OHIO, A CORPORATION OF OHIO

DESIGN FOR A TEXTILE FABRIC

Application filed July 24, 1929. Serial No. 32,177. Term of patent 14 years.

To all whom it may concern:

Be it known that I, BENJAMIN S. NASH, a citizen of the United States, residing at Short Hills, in the county of Essex and State of New Jersey, have invented a new, original, and ornamental Design for Textile Fabric, of which the following is a specification, reference being had to the accompanying drawing, forming part thereof.

In the drawing:—

The figure is a plan view of a piece of textile fabric showing my new design.

The drawing shows a plan view of a piece of textile fabric embodying my design, a unit of which is enclosed within the area outlined by arrows, which unit is repeated in the relation illustrated over the surface of the fabric.

I claim:

The ornamental design for a textile fabric substantially as shown and described.

BENJAMIN S. NASH.
